UNITED STATES PATENT OFFICE.

ROBERT EMMET KEOUGH, OF MONTREAL, QUEBEC, CANADA, ASSIGNOR TO THE AMERICAN FORK & HOE COMPANY, OF CLEVELAND, OHIO, A CORPORATION OF OHIO.

RAIL JOINT.

Application filed April 3, 1926. Serial No. 99,475.

My invention relates to rail joints and has a special application to the problem of prolonging the term of usefulness of the rail joint elements commonly employed for 5 the purpose of joining railroad rails in end to end relation.

It has been found necessary to remove the laterally disposed clamping side bars of rail joints after a certain period of effective 10 use, due to the fact that the movement of trains over the rails employing such joint causes the side bar elements to wear away at the portions of their surfaces wherein contact is had with the rail flanges. These 15 side bar elements are usually made of a good quality of steel, and their replacement is expensive in material and labor required.

An object of my invention, therefore, is to increase the effective life of the side bars 20 employed for the purpose of securely joining longitudinally aligned rails together.

Another object of my invention is to permit the employment of side bar elements having wearing surfaces of inexpensive material, and which, except for my invention, 25 would be worn away even more rapidly than are the like surfaces of the rail joint side bar elements now commonly in use, but which, because of exposure to wear, are now 30 required to be made of a superior wear-resistant material.

Another object of my invention is to effect the production of an element which may be used as a shim or liner, as an article of manufacture, and which may be added to a worn 35 rail joint to effect its continued use in a highly efficient and satisfactory manner.

Other objects of my invention and the invention itself will be readily apparent from 40 the accompanying description, in which description reference will be had to the drawings accompanying this specification and forming a portion thereof.

Referring to the drawings:

45 Fig. 1 shows a sectional view of one embodiment of my invention applied to a rail joint taken on line 1—1 of Fig. 16;

Fig. 2 shows one embodiment of my invention in perspective view;

50 Fig. 3 shows a sectional view on the line 3—3 of Fig. 2;

Fig. 4 shows a perspective view of another embodiment of my invention.

55 Fig. 5 shows a sectional view taken on line 5—5 of Fig. 4;

Fig. 6 shows a perspective view of another embodiment of my invention;

Fig. 7 shows a sectional view taken on the line 7—7 of Fig. 8;

Fig. 8 shows a perspective view of another 60 embodiment of my invention;

Fig. 9 shows a sectional view taken on the line 9—9 of Fig. 6;

Fig. 10 shows a sectional view of another 65 embodiment of my invention applied to a rail joint;

Fig. 11 shows a sectional view taken on the line 11—11 of Figs. 12 and 15;

Figs. 12, 13, 15, 18, 19 and 21 are perspective views, each of differing other 70 embodiments of my invention;

Figs. 14 and 18^a are medial transverse sections of the embodiments of Figs. 13 and 18, respectively;

Fig. 16 shows a rail joint in side elevation; 75

Fig. 17 is a transverse section showing the embodiment of Fig. 6 in use; and

Fig. 20 is a side elevation of the embodiment of Fig. 19 in use. 80

Referring to the drawings, I have illustrated different embodiments of my invention, like reference characters being employed to designate like parts in figures of drawings which show the same embodiment. 85

In rail joints employed for the purpose of securing the abutting ends of railroad rails together, it is the general practice to employ a pair of rail joint side bars, one on either side of the joined rails, compressing these 90 together by means of bolts passing through aligned openings in the side bars and the rail, and in such cases it is usual to employ side bars having inclined upper and lower rail engaging faces for engagement with the under side of the rail head and the upper side of the rail flange, respectively.

It has been found that in use, considerable wear of the rail joint side bar elements and of the contacted portions of the rail head 100 and rail flange occurs, due to pounding of the joined rail ends by the passage of the supporting wheels of heavy railroad trains. It has been found, moreover, that this wear occurs in greater measure as the abutting 105 ends of the rails are approached, and that the wear is progressively less and less in contacting portions of the rail joint side bars and the rail from the abutting ends of the rails along the rails. 110

The practice generally has been to discard the side bars when the wear above mentioned becomes excessive and the rail cannot be securely held by the side bars, even when the securing bolts are tightened by turning the nuts provided upon their ends, such side bars have generally had to be replaced. If any effort has been made to employ shims to take up the wear between the bars and rail, such effort, so far as I am aware, has not prior to my invention attained any considerable degree of success. I find that by employing a shim shown herein in varying forms but in most of the forms of which the shim is tapered in transverse sections from the portion of greatest thickness, at the middle of the shim, to its ends, whereat the shim is much thinner than at the middle, I am enabled to take up the wear substantially commensurable with the amount of the wear of the portions of side bars and rails contacting with the shim. In such constructions, I place the thicker middle portion of the shim at that portion of the joint adjacent the abutting ends of the railroad rails, where the most wear occurs.

In the embodiment shown in Fig. 2, I show a form of my invention wherein a transverse section taken at its middle on the line 3—3 and illustrated at Fig. 3 is much thicker than the shim at either end, the shim tapering gradually from the line of section mentioned to both ends. In practice, such a shim is placed between the finishing face 15 of the side bar 2 and the under side of the rail head flange 9, and extends along the joined ends of two abutting rails for preferably an equal distance from each rail end, as best illustrated in Fig. 16 wherein the 40 form of my invention illustrated in Figs. 2 and 3 is depicted.

It is to be noted that the shim illustrated in the different figures is bent intermediate its top and bottom edges, as shown at 16, this bend being preferably a gradual bend and so made as to cause the top portion 17 and the bottom portion 18 to be disposed at an angle slightly greater than the angle defined by the under face of the rail head flange and the lateral surface of the rail web 19, so that when positioned, as illustrated in Fig. 1, against such under surface of the rail head flange, the remote lower end of the shim will be projected toward the 55 web.

It is also to be noted that I preferably make my improved shim with its angularly disposed portions of different length, the portion 17 being of less length than the downwardly extending portion 18, and in an embodiment of my invention, substantially like that of Figs. 2 and 3 which I have employed in practice, I have made the portions of this shim of such lengths that the upper 65 portion is substantially four-fifths the length

of the lower portion. I do this preferably so that when employing the shim of varying sizes of rails, the same shim may be used on a small sized rail with its portion of lesser length uppermost, and on a larger rail with 70 its portion 18 uppermost and the portion 17 depending therefrom. In other words, the shims of my invention are invertible, and when put in service in inverted position will accommodate a different sized rail than when 75 positioned in the reverse position.

The shims of my invention heretofore described may also be employed between the upper surface of the rail base flange 10 of the rail 1, and the under face of the bar 2, as 80 illustrated in Fig. 1 of the drawings. The shim is so placed in this position that the lower portion 18 rests upon the base flange 10 and the upper portion 17 extends upwardly between the bar 2 and the web portion of the rail 1. If desired shims may also be employed both between the top and the bottom portions of the bar 2 and the rail 1.

Referring now to Figures 4 and 5 of the drawings wherein I have illustrated another 90 embodiment of my invention in which a shim 12 is bent at 55 to form upper and lower portions 56 and 57, grooves 6 are preferably provided on the outer faces of these portions, these grooves being shallow and sufficiently 95 wide so that the shim is not materially weakened. The grooves 6 convey lubricant applied at upper edge portions particularly to the bolts securing the same. It will be readily understood from the foregoing that 100 the lubricant introduced will also reduce the friction between the rails and bars and diminish the amount of wear between the same when the supporting wheels of a railway train pass over the rail joint.

The grooves 6 of the shim 12 also function to relieve the rail joint bar 2, in portions, which when the bolt holes 7 are punched in the shim, are caused to expand or swell. Although the amount of swelling effected 110 thereby is small, it may be enough to prevent contacting of the rail with the said bar except at such expanded or outwardly bulged surfaces of the adjacent bolt holes.

Figs. 6, 9 and 17 of the drawings illustrate another embodiment of my invention wherein the shim 13 is provided on the edge of its upper portion 20 thereof, with an upturned end portion 5 extending throughout the length of the edge of the upper face 20. 115 Accordingly when the shim 13 is applied to a rail joint a channel 21 is formed between the edge of the rail head flange 9 and the upturned portion 5 for collecting applied lubricant and holding the same so as to work down within the grooves between the shim and the underside of the rail head flange 9, as best shown in Fig. 17 of the drawings.

The shim 13 may also be provided on its 130

upper portion 20 and preferably on one surface thereof with grooves 22 similar to the grooves 6 provided on the shim 12, as illustrated in Fig. 4, to provide passages for the 5 lubricant to direct it downwardly between the shim and the rail head flange 9, into the rail joint.

In Figs. 7 and 8 of the drawings, at 14, I illustrate another embodiment of my invention, bent at 61 to form upper and lower portions having provided thereon preferably a series of slightly up-curved portions and alternate slightly down-curved portions 8, presenting a waved surface for the purpose of taking up for the swelling of the bar 2, when the bolt holes 7 are punched therein, and to form grooves which are adapted to function to lubricate the rail joint, and to make the shim compressibly resilient. The shims illustrated in Figs. 1 to 9 and designated with the numerals 3, 12, 13 and 14 are preferably of a good quality of steel and may sometimes be 10 inches long and $2\frac{3}{16}$ inches wide. However, I do not 25 wish to limit myself to these precise dimensions inasmuch as my shim may be employed with rails of different sizes. The shim has its greatest thickness at the middle, and I may make them $\frac{1}{16}$ inch in thickness at the 30 middle portions and gradually taper them in both directions towards their ends, which may be only $1/64$ inch thick. It will be understood that the drawings forming a part of this specification are merely illustrative 35 of various embodiments of my invention and that the dimensions of the various embodiments of my invention may be decreased or increased, according to the size of rail with which they may be used.

In the embodiment illustrated in Figs. 10, 13 and 14 of the drawings, 29 designates a tapered shim bent at 32 and 35 adjacent its ends to provide upper and lower bearing surfaces 23 and 25, respectively. The upper 45 surface 23 is preferably shorter in length than the lower surface 25 and bent at an angle preferably slightly larger than the corresponding angle formed by the under face of the rail head of the rail 34, and fishing 50 angle of bar 2.

The lower portion 25 is bent at an angle preferably slightly greater than the angle of the base flange 30 with respect to the web 59 of the rail 34. The portion 36 of the shim 55 29 has preferably disposed adjacent its lower and upper ends longitudinal openings 30 and 31 adapted for the reception of the projections 26 and 27, respectively, of the bar 40, whereas, due to wear, and re-tightening 60 of the bolts these projections are advanced toward the rail web 59. The upper and lower wearing surfaces 23 and 25 of the shim 29 are integrally connected with main body portion 36 by pairs of connecting portions 65 38 and 39, respectively.

In the embodiment of my invention illustrated in Figs. 11 and 12 of the drawings, 41 designates the body portion of my shim bent at 44 adjacent its upper end and at 45 adjacent its opposite end to form angular wearing surfaces or faces 42 and 43. The angles of these wearing surfaces 42 and 43 preferably correspond to the angles of the wearing surface 23 and 25 of the shim 29 heretofore described. Reference is now directed 70 to the shim illustrated in Fig. 15 of the drawings, illustrating another embodiment of my invention wherein 50 is a relatively narrow stem integrally joining the upper wearing surface 51 and lower wearing surface 52. The upper wearing portion is bent downwardly at 53 while the lower bearing portion 52 is bent upward at 54, both forming a part of the connection between the two portions 51 and 52. The portions 51 and 52 80 are disposed at angles relative to the portion 50 of the shim, corresponding to the angles of the upper and lower portions of my shim 85 illustrated in Figs. 12 and 13.

I contemplate providing any and all of the embodiments of my invention with grooves in the manner illustrated in Figs. 4, 6 and 22 of the drawings, and designated by the numerals 6, 8 and 8, respectively.

In the embodiments of my invention illustrated in Figs. 10 to 15, the edges of the shim may project slightly beyond the outer edges of the rail head flange and the rail base flange, when in use, as best shown in Fig. 10 of the drawings, or may be sometimes employed in embodiments whose edges lie within the flange edges.

As illustrated in Fig. 20, sometimes where one-way railway tracks are employed, the fishing surfaces of the "receiving" rail flange 105 and of the joint bar adjacent thereto are worn to a much greater extent than the similar surfaces relating to the "leaving" rail, the direction of travel of the trains being shown in Fig. 20 by the arrow, the rails being there-in suitably designated. In cases of this kind, I may employ shims having a one-way taper only as illustrated in Fig. 19 and illustrated as being applied in Fig. 20, and in which case the shim is thicker at one end 110 115 adapted to be placed against the end of the "receiving" rail flange, and tapers therefrom to a considerably less thickness at its other end adapted to be disposed remote from the end of the "receiving" rail, the thicker 120 end being shown at 65 and the thin end being that shown at 66. In such a case, also, where a certain amount of lesser wear of the contacting rail joint portions occurs on the under side of the "leaving" rail flange, I 125 may employ the embodiment illustrated in Fig. 21, wherein the shim is tapered from its middle, longitudinally toward both ends, as in the embodiment of Fig. 2 but wherein one longitudinal half portion 67 is thicker 130

in all parts than is the portion 68, the portion 67 being adapted to be placed in the same manner as illustrated in Fig. 20 for the shim 19 and the portion 68 being placed 5 similarly with respect to the "leaving" rail at 69, Fig. 20.

The embodiment of Fig. 21, is claimed 10 separately in an application divisional here-of, Serial No. 326,507, filed December 17, 1928.

In Figs. 18 and 18^a, I show another embodiment of my invention, comprising a shim having its two angularly disposed longitudinally extending portions 70 and 71 15 relatively disposed preferably as described for other embodiments, such as that of Fig. 2, but modified, in that the portion 71 is made thinner throughout than is the portion 70, both portions, however, tapering from 20 enlarged transverse sections at the middle of the shim toward either end where each portion is much thinner than at the shim middle. By this construction, I may invert the angular shim to place either portion be- 25 tween the rail flange fishing surfaces and the fishing surfaces of the rail joint bar, and depending upon the amount of wear re- 30 quired to be taken up by the interposition of the shim. For instance, when the wear is slight, the thinner shim portion 71 would be placed in the crevice caused by the wear between the contacting portions of the rail joint, but when a larger crevice caused by a 35 greater wear of the contacting portions of the rail joint is encountered, the shim portion 70 will be inserted to take up such wear.

All of the shims herein described are preferably made of a good quality of steel, but may be made of various materials, prefer- 40 ably metallic, and I contemplate making them of materials varying in hardness, so that one grade of shims will resist the forces tending to wear away surface portions of the shim to a greater degree than 45 will other grades of shims contemplated herein. I contemplate also making the shims in a grade whose hardness is not more than and preferably less than the hardness of the rail splice bar employed, since such shims 50 may be manufactured much more cheaply than the splice bar, and its replacement may be relatively inexpensive to the cost of replacement of a splice bar. I therefore con- 55 template making three or more grades of shims—one harder than, one equal to and one softer than the splice bar adapted to contact therewith.

Although I have shown but a limited 60 number of embodiments of my invention, I contemplate and herein disclose such combinations of structural characteristics as making both longitudinally extending portions 65 of the shim of other embodiments than that of Fig. 18 of different thicknesses, and I may employ one-way tapered shims otherwise

formed as in any of the embodiments herein illustrated.

Having thus described my invention in several embodiments, I do not wish to limit myself to the said embodiments as I am 70 aware that numerous and extensive departures may be made from the embodiments herein illustrated and/or described but without departing from the spirit of my invention. 75

I claim:

1. As an article of manufacture, a liner element of hard metallic material, adapted to be inserted between worn contacting portions of a pair of rails and a rail joint side 80 bar secured to each of the rails, said element being thickened toward portions thereof disposed adjacent the ends of the rails and tapering in either direction therefrom. 85

2. As an article of manufacture, a shim of 90 wear-resisting metallic material for rail joints, adapted to be inserted between portions of a rail and a rail joint side bar which have become worn, said shim being thickened in its portion adapted to be disposed 95 between the bar and rail flange adjacent the end of the rail, and progressively tapered therefrom in portions progressively more and more distant from the said rail end, and of substantially uniform thickness along 100 lines of section extending transversely to the shim and rail.

3. As an article of manufacture, a metallic 105 shim for rail joints, adapted to be inserted between a rail and portions of a rail joint side bar which have become worn, said shim being thickened in its portion adapted to be disposed between the bar and rail flange adjacent the end of the rail and progressively 110 tapered therefrom in portions more and more distant from the said rail end, said shim being bent intermediate its edges to form an upper shim portion adapted to be disposed between the fishing faces of the bar and rail head. 115

4. As an article of manufacture, a metallic 120 shim for rail joints, adapted to be inserted between a rail and portions of a rail joint side bar secured thereto and contacting therewith, the contacting surfaces of which have become worn, said shim being thickened in portions adapted to be disposed between the bar and the rail adjacent the joining ends of the rail and being tapered from its thickest portion to its end portions, said 125 shim being bent intermediate its edges to form an upper longitudinal shim wearing portion adapted to be disposed between the fishing faces of the bar and rail flange. 130

5. As an article of manufacture, a metal- 125 lic liner element, adapted to be inserted be- 130 tween worn contacting portions of a pair of rails and a rail joint side bar bolted against a side of each of the rails, said ele- 130 ment being thickened toward portions there-

of disposed adjacent the ends of the rails, and tapering in either direction therefrom, said element having formed thereon grooves for directing lubricant to portions of the 5 rail joint to be lubricated.

6. As an article of manufacture, a liner element of hard metallic material, adapted to be inserted between worn contacting portions of a pair of rails and a rail joint side 10 bar bolted against a side of each of the rails, said element being thickened toward portions thereof disposed adjacent the ends of the rails and tapering in either direction therefrom, said liner element having lubricant directing grooves on its upper surface. 15

7. As an article of manufacture, a liner element of hard metallic material, adapted to be inserted between worn contacting portions of a pair of rails and a rail joint side 20 bar bolted against a side of each of the rails, said element being thickened in portions thereof disposed adjacent the ends of the rails, and tapering in either direction therefrom, said liner having portions of its surface, adapted to be placed adjacent the bolt 25 holes through the bar, relieved.

8. As an article of manufacture, a metallic shim for rail joints, adapted to be inserted between a rail and portions of a rail joint side bar which have become worn, said shim being thickened in its portion 30 adapted to be disposed between the bar and rail flange adjacent the end of the rail, and progressively tapered therefrom in portions 35 progressively more and more distant from the said rail end, said shim being bent intermediate its edges to form an upper shim portion adapted to be disposed between the fishing faces of the bar and rail head, and a lower portion adapted to be projected 40 within the space between the upper end of the bar and the web of the rail.

9. As an article of manufacture, a liner element of hard metallic material adapted 45 to be inserted between worn contacting portions of a pair of rails and a rail joint side bar bolted against a side of each of the rails, said element being thickened toward portions thereof disposed adjacent the ends 50 of the rails and tapering in either direction therefrom and bent longitudinally at one side of its longitudinal medial axis to so form it that it comprises a pair of interchangeable shim portions disposed at an obtuse angle to each other, said element adapted 55 to be placed with either one of the said portions between the upper face of the side bar and the fishing surface of the rail head flange and the other portion between the rail web and the upper portion of the bar. 60

10. As an article of manufacture, a liner element of hard inherently resilient metallic material adapted to be inserted between worn contacting portions of a pair of rails and a rail joint side bar bolted against a 65

side of each of the rails, said element being thickened toward portions thereof disposed adjacent the ends of the rails and tapering in either direction therefrom, and corrugated transversely of the longitudinal 70 axis of the rail against which it is placed.

11. As an article of manufacture, a liner element of hard metallic material adapted to be inserted between worn contacting portions of a pair of rails and a rail joint side 75 bar bolted against a side of each of the rails, said element being thickened toward portions thereof disposed adjacent the ends of the rails and tapering in either direction therefrom, said element being of such a 80 length as to extend throughout the major portion of a crevice formed by wear of contactable portions of the pair of rails and the side bar bolted thereto.

12. A metallic rail joint shim insertable 85 between worn portions of a rail joint comprising the lower surface of a rail head flange and a side bar worn by engagement therewith, said shim varying in thickness in portions variably disposed longitudinally of 90 the joint to compensate for the worn away portions thereof, said shim being of equal thickness along all lines of cross-section extending transversely to the rail joint.

13. A metallic rail point shim having an 95 end portion of less thickness than another portion longitudinally spaced therefrom and of uniform thickness along all transversely extending lines of section.

14. A rail joint shim comprising a strip 100 of metallic material having two longitudinally extending portions angularly disposed relative to each other, the shim being invertible to place either of said portions between worn portions of a rail joint, said shim being of 105 graduated thickness to compensate for the graduated wearing away of portions of the rail joint, increasing in amount toward the middle of the joint.

15. A rail joint shim comprising a strip 110 of metallic material having two longitudinally extending portions angularly disposed relative to each other, the shim being invertible to place either of said portions between worn portions of a rail joint, one of said 115 portions being of greater width than the other portion and adaptable for use in a rail joint comprising a larger sized rail.

16. A rail joint shim comprising a strip 120 of metallic material having two longitudinally extending portions angularly disposed relative to each other, the shim being invertible to place either of said portions between worn portions of a rail joint, one of 125 said portions being thicker than the other portion.

17. A rail joint shim comprising a strip of metallic material having two longitudinally extending portions angularly disposed relative to each other, the shim being invertible 130

to place either of said portions between worn portions of a rail joint, both of said portions being suitably thickened in portions to fill a crevice formed in worn portions of a rail joint.

18. A rail joint shim comprising a strip of hard material having two longitudinally extending portions angularly disposed relative to each other, the shim being invertible to place either of said portions between worn portions of a rail joint, one of said portions being thicker in some parts than in other parts thereof, whereby all parts of said portion, when inserted between worn parts of a rail joint, may fill the space formerly occupied by the worn away parts of the joint.

19. A rail joint shim comprising a strip of metallic material having two longitudinally extending portions angularly disposed relative to each other, the shim being invertible to place either of said portions between worn portions of a rail joint, each of said portions being thicker in some parts than in other parts thereof, whereby all parts of said portions, when inserted between worn parts of a rail joint, may fill the space formerly occupied by the worn away parts of the joint.

20. A rail joint shim comprising a strip of metallic material having two longitudinally extending portions angularly disposed relative to each other, the shim being invertible to place either of said portions between worn portions of a rail joint, one of said portions being thicker in some parts than in other parts thereof, whereby all parts of

said portion, when inserted between worn parts of a rail joint, may fill the space formerly occupied by the worn away parts of the joint, the other of said portions having parts thereof disposed in transverse alignment with parts of the first said portion of a thickness differing therefrom.

21. A shim for rail joints, adapted to be placed between a rail joint side bar and a pair of substantially abutting rails, of metallic material of decreasing thickness towards its ends.

22. A shim for rail joints adapted to be placed between a rail joint side bar and a pair of substantially abutting rails, of metallic material of decreasing thickness toward its ends, the thickness of all portions of the shim adapted to contact with the rail being approximately of such dimension as to occupy the space previously occupied by worn away portions of the rail and side bar.

23. A rail joint shim comprising a strip of metallic material having two longitudinally extending portions angularly disposed relative to each other, the shim being invertible to place either of said portions in the crevice formed between worn parts of a rail joint, both of said portions being suitably thickened in portions to substantially fill the crevice, one of said portions being of greater width than the other portion.

In testimony whereof I hereunto affix my signature this 27th day of March, 1926.

ROBERT EMMET KEOUGH.
